SCORE KEEPER

Austin B. Barbeaux, West New Brighton,
Staten Island, N. Y.

Application February 23, 1939, Serial No. 258,088

4 Claims. (Cl. 235—1)

This invention relates to a game score keeper and more particularly it refers to a device for indicating a golf score, such device being associated with and forming a part of one club used in playing the game of golf.

It has been heretofore proposed to associate a score-keeping register with an instrument for playing a game, such as a golf club but such devices as known to the prior art have been no more than an indicating means affixed to said instrument. One worker in this field has suggested that a score pad be affixed to the rear face of a golf club head and that a pencil be carried in a hole in the shaft. This is merely a convenient method of carrying a conventional score pad.

It has also been suggested that a rotatable collar be mounted upon the handle end of the club. The collar of this device carries numerical indicia and an arrow on the club handle adjacent the collar indicates the number of strokes taken with the particular club. It is obvious that as this club is carried in a bag the indicating device will be at the bottom of the bag hidden from sight.

I have designed a score keeper in combination with a club peculiarly adapted to the golf game which may possibly be modified to adapt it for use with other games now known or yet to be devised. Preferably, my indicator is mounted upon the shaft of a putter adjacent the head thereof and comprises a plurality of indicating devices whereby the score of a complete game may be kept upon an implement carried during the game and used therein.

The advantages of such a device are many. The inconvenience of carrying a cardboard scoring sheet and a pencil throughout a golf game is well known to those who have played this game. The scorecard invariably becomes crumpled, dirty and is generally in an inconvenient place at the end of each hole. Pencils of a size small enough to be convenient in use are easily lost and the points usually become broken.

It is accordingly an object of this invention to provide a scorekeeping device for the golf game whereby all the elements of the score may be entered on a unitary mechanism associated with one club of the series used during the game.

The invention contemplates specifically that the scoring device shall be associated with the putter since this is the club generally used in finishing a hole and is therefore in the hands of the player at the time the score is complete for each hole. As a further object the invention con-

templates a scorekeeping device capable of registering the entire score for a normal game of 18 holes.

Other objects and advantages of this invention will be apparent from a consideration of the following discussion in view of the attached drawing, wherein:

Figure 1 is a rear elevation of a golf club embodying the scorekeeping structure of this invention;

Figure 2 is a cross-section on line 2—2 of Figure 1;

Figure 3 is a perspective view of one of the indicating rings employed;

Figure 4 is a perspective view of a spacing ring; and

Figure 5 is a partial perspective view of that portion of the club shaft on which the indicating members are mounted.

The preferred embodiment of the invention comprises a putter having indicating devices on the shaft adjacent the head as illustrated in Figure 1. The shaft 10 is joined to a head 11 by riveting as indicated generally at 12. For a portion of its length adjacent the head the shaft 10 is of reduced diameter and has a plurality of indicating rings 13 mounted thereabout. Each indicating ring 13 has a series of numbers stamped, engraved or otherwise marked about its periphery in sequence. A raised knurled portion 14 is provided at one edge of each ring in order that the ring may be readily rotated by the fingers of the user.

For reasons more fully brought out herein-after, the rings are grouped by interposing spacing rings 15 of a color contrasting with the color of indicating rings 13 at certain intervals. At opposite ends of the region of the shaft 10 occupied by rings 13 and 15 the words "out" and "in" together with arrows pointing toward the said region are marked as by stamping, engraving or the like.

As shown in Figure 5 the shaft underlying the indicating rings 13 and the spacing rings 15 is provided with a plurality of grooves 16. A projection 17 on the inner surface of each of the rings 13 is positioned to engage the grooves 16. The wall of indicating ring 13 is cut to form a slot 18 for a portion of its circumference adjacent the raised knurled portion 14 to impart a spring action to that part of the ring on which the projection 17 is formed. It must be clearly understood that the dimensions of the grooves 16 and edges 17 are preferably much smaller than shown here and the dimensions thereof in

the drawing are exaggerated for purposes of illustration. In that embodiment of the invention found to be most suitable, the grooves 16 are very narrow and very shallow and may be produced by scoring the golf club shaft in a suitable manner. Similarly the ridges 17 are preferably so small that they may be referred to as hairlines.

The number of grooves 16 and ridges 17 shown in the appended drawing are not to be regarded as controlling of the invention. Any number of cooperating grooves and ridges which will give a number of positions for the indicating rings 13 corresponding to the number of scoring indicia about the outer surface of the said rings, 15 will be found suitable. Although a single projection 17 is preferred since it may be given a spring action by reason of the ring wall being free of the portion 14 for a portion of its length, any number (from one to ten) of projections 17 20 will give advantageous results.

I prefer to mark scoring indicia about the surface of the said rings 13 using the digits from 0 to 9 in order and I therefore provide for ten possible positions for the scoring rings. In order 25 to obtain ten possible positions as aforesaid, it is preferred that the interior of the rings 13 be provided with one ridge 17 and that the shaft be scored or otherwise provided with ten grooves 16. Since the primary function of the spacing 30 rings 15 is to give a convenient grouping of the indicating rings 13, it is relatively immaterial whether or not the rings 15 are provided with ridges corresponding to the ridges 17 of the indicating rings 13. If it is desired that the rings 35 15 be rigidly positioned upon the shaft 10 the said spacing rings may be preformed of relatively small internal diameter and shrunk onto the shaft 10 after heating or they may be fitted with a plurality of ridges in similar fashion to the 40 construction of the indicating rings 13.

In constructing or assembling the score keeper of my invention, I may start with a shaft and head designed for any type of putter but I prefer to use a putter having a steel shaft. I first 45 reduce the diameter of a portion of the putter shaft adjacent the head end thereof for a length suitable to receive my novel indicating device. This region of reduced diameter is then provided with grooves 16 as by scoring or any other suitable 50 machining technique. The word "out" together with an arrow may be stamped directly on the shaft above the portion of reduced diameter or it may be engraved or otherwise marked upon a collar which is subsequently fitted on the 55 shaft and rigidly positioned with respect thereto. Thereafter the rings 15 and 13 are assembled upon the reduced diameter portion of the shaft in a desired relation and the spacing rings 15 are rigidly fixed to the shaft as desired. Alternatively, the rings 15 may fit loosely on the 60 shaft if desired. A collar 18 having the word "in" and an arrow stamped or otherwise marked thereon is now slipped over the end of the shaft and rigidly fixed thereto by any suitable 65 means. Thereafter the club head is affixed to the shaft by riveting or any other conventional method.

As noted above, the dimensions shown here 70 are purely for purposes of illustration and are exaggerated to a material extent. In order to enable others skilled in the art to practice the preferred embodiment of this invention, the approximate measurements of the various portions of a putter which have been found to give very 75 good results are set forth below.

A steel shaft designed for a putter and having a diameter of approximately $\frac{1}{16}$ " is machined down to about $\frac{3}{16}$ " along that portion of its length adjacent the head which is desired to carry the indicating indicia. The indicating rings 13 are extremely thin walled and have a total width parallel to the axis thereof of about $\frac{5}{16}$ " of which $\frac{1}{4}$ " carries the indicating indicia while $\frac{1}{16}$ " is raised and knurled to provide a finger grip. Spacing rings 15 have about the same 10 wall thickness and are about $\frac{1}{16}$ " in width. These latter were colored black to give a good contrast with the light colored metal of the indicating rings 13. As has been pointed out above the grooves 16 and ridges 17 are of very small dimension and are difficult to define numerically. 15

It will be noted that the arrows at the ends of the indicating indicia define a line along which lies one digit of each of the rings 13 when each of the said rings 13 is held in position by the 20 cooperating ridges 17 and grooves 16. I have so grouped the indicating rings 13 by interposing spacing rings 15 that provision is made for a two-digit number adjacent each of the ends of the indicating mechanism. The pair of indicating rings adjacent the word "out" are adapted to indicate the total score for the first nine holes of a normal eighteen hole game, while the pair of indicating rings adjacent the word "in" are intended to register the score for the second nine 30 holes.

Each of the nine indicating rings 13 between the two end pairs of such rings are intended to indicate the score for one hole of a normal nine 35 hole course.

Although my novel scoring device may be incorporated with a club of any type normally used in a golf game, I prefer that it shall be made a part of a putter since this club usually is the last one used unless the player is unusually skilled and/or lucky and holes out with a shot from the fairway. After holing out, the player holds the putter by grasping the shaft in the left hand with the club head hanging downward and rotates the proper scoring ring 13 to a position such that a digit on said ring corresponding to the number of strokes taken for the hole just finished lies along the line defined by the arrows at each end of the scoring mechanism. As each digit successively comes into the said 40 line the contact of ridges 17 and grooves 16 will produce a clearly audible click and the meshing of the said parts will be productive of a distinctly perceptible difference in the feeling of the ring 13 during rotation. The raised knurled portion 14 of each ring 13 renders rotation of the ring very easy and the meshing of ridge 17 with one of the grooves 16 positively retains the ring 13 in desired position against shock or accidental dislocation in normal handling of the 45 club.

During the playing of an 18 hole course the score for each of the first nine holes, which nine hole course constitutes half of the game, will be indicated from left to right starting with the 50 third ring 13 from the left hand end of the scoring mechanism. Each of the nine scoring rings 13 is grouped with two other such rings by the interposition of the spacing rings 15 thereby 55 making it easy to determine at a glance what hole is being played or the score for any particular hole of the nine. After finishing nine holes the total of the individual scores of these 60 nine holes is calculated and that total is registered on the two rings adjacent the word "out." 65

The nine rings 13 in the middle portion of the scoring device are then rotated to register zero and the second nine holes are played indicating the score for each of the second nine in the same 5 manner as indicated above.

Upon finishing the eighteen hole game, the total score for the second nine is calculated and indicated on the two rings 13 adjacent the word "in." The indicating device of the present invention thus provides a means for registering the total score of a normal eighteen hole golf game as two separate scores, one for each of the nine hole courses making up the game. This is the form in which most golfers desire to have 10 their score available. It will be apparent that a greater number of rings may be provided in order that the individual scores for each of the eighteen holes can be registered. However, it is believed that the present form is more 15 convenient in use and suits the needs of a greater number of golfers.

It is well recognized by golfers that the important feature of a score is the individual score for each hole. Most players prefer to compare 20 a score hole by hole rather than on the total for a course since it is only in this manner that faults may be evaluated and corrected. The present device permits such a comparison and enables the player to use his score to the best advantage in improving his game.

The present invention renders unnecessary the usual irritating score card and pencil. It makes possible the register of a score on a device normally in the golfer's hands at the time a hole 25 is finished and the final score therefor is known. A further advantage of this invention lies in the fact that the score registered is immediately available to the player at all times by reason of the fact that it is on that portion of one of 30 the clubs near the top of the bag and is readily pulled out part way and oriented by turning the club so that the face of the head is downward as the person reading the score holds the club below his eyes and the club shaft rotates by reason of 35 the weight of the head. While the invention contemplates the use of the present scoring device on any club of the set normally used by a golfer, I have found that it is much more convenient to associate the present device with the putter 40 for reasons noted above.

It is to be understood that the present disclosure is not exhaustive or limiting of the invention but on the contrary is described as exemplary of the principles and operation of a preferred embodiment thereof in order that others skilled in the art may adapt the same to any desired use.

I claim:

1. A score indicating device comprising a shaft and a score indicating ring mounted for rotation about said shaft, a plurality of numerical indicia successively disposed about said score indicating ring, a raised knurled portion on said ring and separated from that portion of said ring bearing said indicia for a portion of the circumference thereof, a ridge on the interior of said ring parallel to the axis thereof and a plurality of grooves in said shaft parallel to said ridge, said ridge being on the interior of that portion of said ring bearing said indicia which is separated from said knurled portion. 5

2. An indicating device comprising a shaft and an indicating ring mounted for rotation about said shaft, a plurality of indicia successively disposed about said ring, a raised knurled portion on said ring and separated from that portion of said ring bearing said indicia for a portion of the circumference thereof, at least one ridge on the interior of said ring parallel to the axis thereof and a plurality of grooves in said shaft parallel to said ridge, said ridge being on the interior of a portion of said ring bearing said indicia which is separated from said knurled portion. 10

3. An indicating device comprising a shaft and an indicating ring mounted for rotation about said shaft, said ring being of substantially cylindrical form and having one portion thereof separated from the remainder of the ring by a circumferential opening through the wall of said ring extending for a portion of the circumference thereof to afford a weakened portion of 15 said ring capable of distortion, at least one ridge on the interior of said weakened portion parallel to the axis of said ring and a plurality of grooves 20 in said shaft parallel to said ridge. 25

4. An indicating device comprising a shaft and an indicating ring capable of distortion mounted for rotation about said shaft, a plurality of indicia successively disposed about said ring, a rigid means adapted to be gripped by 40 the fingers for manual rotation of the ring attached to that portion of the ring bearing said indicia for a portion only of the circumference thereof, at least one ridge on the interior of said ring parallel to the axis thereof and a plurality of grooves in said shaft parallel to said ridge, 45 said ridge being on the interior of that portion of said ring which is not secured to said rigid means. 50
